[57] CLAIM

The ornamental design for a tweezers or similar article, as shown and described.

DESCRIPTION

FIG. 1 is a perspective view of tweezers or a similar article showing my new design;

FIG. 2 is a top plan view thereof;

FIG. 3 is a left side elevational view thereof;

FIG. 4 is a front end elevational view thereof;

FIG. 5 is a rear end elevational view thereof;

FIG. 6 is a bottom plan view thereof;

FIG. 7 is a right side elevational view thereof;

FIG. 8 is a perspective view of a second embodiment;

FIG. 9 is a top plan view thereof;

FIG. 10 is a left side elevational view thereof;

FIG. 11 is a front end elevational view thereof;

FIG. 12 is a rear end elevational view thereof;

FIG. 13 is a bottom plan view thereof;

FIG. 14 is a right side elevational view thereof;

FIG. 15 is a perspective view of a third embodiment;

FIG. 16 is a top plan view thereof;

FIG. 17 is a left side elevational view thereof;

FIG. 18 is a front end elevational view thereof;

FIG. 19 is a rear end elevational view thereof;

FIG. 20 is a bottom plane view thereof; and,

FIG. 21 is a right side elevational view thereof.
